CALK DEVICE

Howard M. Pierce and John H. Hermson, Brooklyn, N. Y., assignors to A. G. Spalding & Bros. Inc., New York, N. Y., a corporation of Delaware

Application May 8, 1939, Serial No. 272,351

13 Claims.

(Cl. 36—59)

This invention relates to improved devices for securing calks or cleats to the soles of shoes, particularly shoes used in various sports such for example as football and soccer.

It is of the utmost importance that the calks or cleats be so mounted that they will not inadvertently become loose and will be maintained in place even when subjected to the most severe usage.

It is, therefore, an object of the invention to provide a calk device which may be most effectively held in place on a shoe sole.

It is another object of the invention to provide a calk device which may be most easily applied to the sole.

One of the common expedients heretofore utilized in securing calks or cleats to a shoe sole involves the provision of a threaded stud. Sometimes the cleat is initially fixed to the stud and the latter screwed into the sole, and sometimes the stud is initially fixed to the sole and the cleat then screwed on the stud. In each of these variations of this expedient there is a problem of holding the calk and the threaded stud against turning and thereby becoming loose relative to the sole.

Another important object of the present invention, therefore, is to provide a calk device involving the use of a threaded stud, in which the calk or cleat and the threaded stud are effectively held against turning and unscrewing relative to the sole.

In the attainment of the above and other objects which will hereinafter appear there is provided as a feature of the invention a washer which may be effectively secured to the calk holding stud and which is provided not only with means for gripping the sole but also with projecting means for holding the calk against inadvertent rotation.

Another feature of the invention resides in providing a deformable washer with a sole gripping projection extending from the underside of a portion normally bent to extend away from the sole, whereby it is possible to screw the washer tightly against the sole without interference from the gripping projection and then to subsequently flatten the bent portion to cause the projection to bite into the sole.

Another feature resides in providing a washer with a tubular stem which supports the calk holding stud in an aperture in the shoe sole.

Another feature of the invention resides in providing a calk device of the type having a screw stud initially fixed to the calk and then

screwed into the sole, in which very efficient and economically produced means are provided for securely holding the calk against unscrewing relative to the sole.

5 A further feature resides in the provision of a calk securing device involving a washer of compressible material, such as leather or rubber, which is inserted on the calk holding stud intermediate the base of the calk and the sole and is adapted to grip the base and hold the calk against inadvertent rotation.

Yet another feature resides in the provision of projections on the base of the calk which co-operate with a washer intermediate the sole and the calk for effectively holding the latter against inadvertent rotation.

Another important feature of the invention resides in providing an internally threaded tubular member adapted to be inserted in an aperture 20 in the shoe sole and to receive the threaded stem of a washer which is provided not only with projections for gripping the sole, but also with projections for holding the calk against inadvertent rotation.

25 Another feature of the invention resides in providing a calk holding stud with very effective means for firmly holding the stud relative to the calk body when it is embedded therein.

Other objects and features will hereinafter 30 appear.

In the drawing:

Figure 1 is an exploded view showing the various elements of the present preferred form of calk device before association with the shoe sole, 35 portions of the insert member and of the stemmed washer being broken away to enable a clearer illustration.

Fig. 2 is an exploded view partially in section, similar to Fig. 1, but showing the insert member 40 and the stemmed washer associated with the shoe sole.

Fig. 2A is a detail view looking downwardly at the calk holding stud.

Fig. 3 is a view partially in section showing the device fully assembled and in operative position on the shoe sole.

Fig. 4 is a view of the side of the stemmed washer which faces the sole.

Fig. 5 is a view showing the base of the calk.

Fig. 6 is a view showing the base of the calk illustrated in Fig. 7.

Fig. 7 is a view similar to Fig. 2 but showing a modified form of the invention.

Fig. 8 is a view similar to Fig. 7 but showing another modified form of the invention.

Before describing the present improvements and mode of operation thereof in detail it should be understood that the invention is not limited to the details of construction and arrangement of parts shown in the accompanying drawing, which are merely illustrative of the present preferred embodiments, since the invention is capable of other embodiments, and the phraseology employed is for the purpose of description and not of limitation.

Referring more particularly to the drawing and first to Figs. 1 through 5, there is shown a section of a shoe sole 10 which may be of conventional construction, including an inner or upper layer 11 and an outer or lower layer 12.

The calk device 13 provided by the present invention includes, as is conventional, a calk or cleat 14 of rubber or other suitable material, which as shown may be frusto-conical in shape and formed with a base 15 from which extends a threaded stem or stud 16. Preferably, webs 17 and 18 extending respectively longitudinally and transversely of the stud are provided to form a head 19 for locking the stud against movement relative to the calk 14.

As shown most clearly in Fig. 2A, the transverse web 18 is preferably of multisided form. Of importance it is to be noted that a plurality of recesses 18a are provided in the edges of the transverse web to receive the body material of the calk 14 and thus serve to hold the stud against adverse rotation relative to the calk. Also of importance attention is directed to the fact that the longitudinally extending web 17 is so formed and positioned that the side edges 17a and 17b thereof extend outwardly to be in substantial alignment with two of the recesses 18a in the transverse web 18.

With this construction the longitudinally extending web 17 together with the recesses 18a in the transverse web effectively hold the stud against adverse rotation relative to the body of the calk, while the transverse web 18 serves to maintain the stud against adverse longitudinal movement in the calk body. And, of particular importance, the side edges 17a and 17b of the web 17 by overlying the transverse web 18 define in effect notches into which the body material of the calk extends to further secure the stud against movement relative to the calk. Also, because the side edges 17a and 17b of the web 17 extend beyond the edges of the transverse web 18 defined by the recesses 18a, a substantial thickness of supporting body material is interposed between the side edges 17a and 17b and the calk base. A very strong and effective securing of the stud 16 in the calk is thus achieved.

For securing the calk to the sole 10 there is provided an interiorly threaded tubular insert member 20 adapted to be inserted in a suitable aperture 21 in the shoe sole. A laterally extending flange 22 formed at one end of the insert member is adapted to overlie the upper side 23 of the sole and is provided with a plurality of circumferential disposed prongs 24 for engaging the sole and holding the insert against rotation relative thereto.

Of importance, there is associated with the insert member 20 a novel stemmed washer 25 having a deformable flange section 26 bent into substantially U-shape to provide portions 27 which extend away from the sole, and having an interiorly and exteriorly threaded tubular stem 28 adapted to be screwed into the insert mem-

ber 20. Preferably, and as shown, the threads 29 formed in the insert member 20 terminate in a slightly enlarged bore 30 formed in the end 31 of the insert member. This enlarged bore accommodates the unthreaded portion 32 of the stem 28 and insures the washer 25 being screwed tightly against the sole.

It is to be particularly noted that prongs 33 are provided on the bent portions 27 of the washer which, as shown in Fig. 2, are clear of the sole when the washer 25 is initially screwed in place but which, as shown in Fig. 3, are adapted to bite into and securely grip the sole when the washer is flattened. This feature is most advantageous in the assembly of the device as it is thereby possible to screw the washer tightly against the sole without interference with the prongs 33 and then subsequently to flatten the bent portions 27 to cause the prongs to grip and bite into the underside 34 of the sole. Moreover, because the prongs 33 are clear of the sole during the screwing up of the washer, they do not cut into the sole to form adverse grooves which would prevent the secure holding action achieved by forcing the prongs cleanly into an uncut sole. Also, the bent portions 27 offer a convenient means for gripping the washer during the screwing or tightening operation. Thus, a worker may merely grasp the bent portions in his fingers and spin the washer into position, and if a pair of pliers or the like is used the bent portions may be easily gripped thereby.

Also of importance it is to be noted that projections 35 are formed on the washer to extend toward the base 15 of the calk. As shown, the projections 35 and the prongs 33 may be conveniently formed by lancing or by bulging out integral parts of the washer. However, they may be formed in any other suitable manner.

With this construction, when the threaded calk stud 16 is screwed tightly into the tubular stem 28 of the washer 25, the base 15 of the calk 14 is drawn firmly against the gripping projections 35 and the calk is securely held thereby against inadvertent rotation relative to the washer 25 which in turn is held against rotation relative to the sole 12 and the insert member 20 by the prongs 33.

As shown a central recess 36 is formed in the base 15 of the calk for receiving the projections 35, and preferably a plurality of radially extending ribs 37 in the form of ratchet teeth are formed on the bottom 38 of the recess for cooperation with the projections 35 in holding the calk against unscrewing. The inherent resiliency of the projections 35 which are lanced out of the preferably metallic washer 25 causes the latter to act like spring pressed pawls. This action is accentuated when the calk and ribs 37 are formed of a compressible or resilient material such as rubber. Thus when the calk is rotated in one direction to be screwed toward the sole, the inclined faces 39 of the ribs readily slide over the projections 35, but any tendency of the calk to rotate in the other direction is resisted by the projections engaging the substantially vertical sides 40 of the ribs. A very effective ratchet or locking means is thereby provided for maintaining the calk securely in position.

While, as shown, the ribs 37 are in the form of ratchet teeth it will be readily understood that the ribs may be formed either with two inclined faces or with two vertical sides. Such constructions will likewise serve to cooperate

with the projections 35 in holding the calk against inadvertent rotation, although not as satisfactorily as when ribs are formed to simulate true ratchet teeth.

In the association of the calk device 13 with a shoe sole, it is merely necessary to push the insert member 20 into a preformed aperture in the shoe sole and embed the prongs 24 in the upper side of the sole. The stemmed washer 25 is then screwed in place and the bent up portions 27 flattened by any suitable tool to force the prongs 33 into the underside of the sole. Then the threaded stud 16 is screwed into the threaded stem of the washer to draw the ribbed base of the calk securely against the washer and into interengagement with the projections 35.

In Figs. 6 and 7 a modified form of calk device 13a is shown. In this form a calk 14a is provided which does not have a stud initially fixed thereto as in the form shown in Figs. 1 through 5, but which includes a calk holding screw member 41 with a threaded shank 42 and a head 43, insertable in a preformed aperture 44 in the sole 10. When the screw member 41 is inserted in the aperture the threaded shank 42 projects downwardly through the aperture 44 to receive the modified calk 14a and the head 43 overlies and is embedded in the upper side 23 of the sole. Preferably, and as shown, radially extending webs or fins 45 are formed on the head to bite into the sole and hold the screw member against adverse rotation.

Of importance, there is provided with this modified calk device 13a a modified stemmed washer 25a which like the stemmed washer 25 first described has a deformable flange section 26 initially bent, as shown in dotted lines in Fig. 7, into substantially a U-shape to provide portions 27 which initially extend away from the sole but which are adapted, as shown in full lines, to be flattened on the sole and thereby force the prongs 33 into the underside of the sole. Also, like the washer 25, the modified washer 25a is formed with an interiorly threaded tubular stem 28a which as shown, however, may be shorter than the stem 28 and provided with an unthreaded or smooth outer surface.

In associating the modified calk device with a sole, the screw member 41 may be first inserted in the aperture 44 and the stemmed washer 25a then screwed thereon to draw the tubular stem into the aperture 44 to thereby support the threaded shank in the sole. When the washer is thus screwed tightly in place the bent portions 27 are flattened to force the prongs 33 into the sole. The washer, therefore, is effectively held against adverse rotation by the prongs 33, and by its threaded connection with the screw member 41 not only is held against movement away from the underside of the sole but serves to maintain the webbed head 43 of the screw member firmly embedded in the upper side of the sole.

The modified calk 14a, which preferably is provided with an internally threaded insert 46 embedded therein, may then be screwed on the threaded shank 42 and thus be drawn firmly against the washer 25a on the sole. As shown, the base 15 of the modified calk is formed with a recess 36a having a plain bottom 38a which is gripped by projections 35 formed on the washer 25a exactly the same as the projections formed on the stemmed washer 25 first described. However, while the bottom of the recess 36a in the base of the calk 14a is illustrated as plain it will

be readily appreciated that the bottom 38a may be formed with gripping ribs as embodied in the calk 14 shown in Fig. 5. Likewise it will be appreciated that if desired the calk 14 shown in Fig. 5, like the calk shown in Fig. 6, may be formed with a recess having a plain bottom.

In Fig. 8 another modified calk device 13b is shown. It, like the calk device 13a shown in Fig. 7, involves a calk 14b preferably provided with a threaded insert 46 and adapted to be screwed on the threaded shank 42 of a screw member 41 inserted in an aperture 44b formed in the shoe sole 10. The screw member 41, as shown, is exactly the same as the one illustrated in Fig. 7, with a head 43 provided with holding webs 45 and embedded in the sole.

In the modified calk device 13b, a slightly modified washer 25b is utilized which like the stemmed washer 25a shown in Fig. 7, has a threaded connection with the shank 42 of the screw member. It may be flat, or initially bent into a substantially U-shape, as shown in dotted lines, to provide portions 50 initially extending away from the sole and formed with prongs 51 which advantageously may be lanced out of the washer and are adapted to bite into the sole when the washer is flattened. However, as shown, no tubular threaded stem is formed on the washer, the threaded connection between the washer 25b and the shank 42 being provided by a single thread 58 defining the shank receiving aperture in the washer. Such a tubular stem may be provided, however, if desired.

Of particular importance there is inserted on the threaded shank 42 intermediate the main and preferably metallic washer 52 and the base 15 of the calk 14b a washer 53 of compressible material such as rubber or leather, which when the calk is screwed tightly in place effectively grips the main washer 25b and the calk and holds the latter against inadvertent rotation.

Preferably, and as shown, projecting ribs 54 are pushed out of the main washer 25b to extend toward the base 41 of the calk. While these ribs 54 are shown as extending radially for an appreciable extent they may, if desired be formed like the simple projections 35 on the stemmed washers 25 and 25a. Also, preferably ribs 37 are formed in the recess 36 in the base of the calk 14b exactly the same as the ribs on the calk shown in Fig. 5. With this construction the ribs 54 on the main washer 25b and the ribs 37 on the calk 14b both grip the compressible washer 53 and the calk is thus most effectively held against adverse rotation.

This same compressible washer 53 may, if desired and with good effect, be utilized with each of the other calk devices 13 and 13a shown in Figs. 1 through 7. When so utilized the washer supplements the action of the projections 35 and ribs 37 in firmly holding the calk and maintaining the same in tightened position on the sole.

With each of the forms of the invention, washers are provided which have a threaded connection with a member firmly embedded in the sole, which have projecting means for not only gripping the sole but also for cooperating in holding the calk against adverse rotation, and which are initially formed with portions extending away from the sole but adapted to be flattened and to push gripping prongs into the sole after the washer has been tightly screwed in place.

Variations and modifications may be made within the scope of this invention and portions of the improvements may be used without others.

Having thus described the invention, what is claimed as new is:

1. In a calk device for attachment to a shoe sole, a calk having a base; a screw member for connecting said calk to the sole; a washer insertable on said screw member intermediate the sole and said calk having projecting means extending toward said base for maintaining the calk against inadvertent rotation; a deformable portion on said washer normally extending away from and adapted to be flattened relative to said sole; and projecting means on said deformable portion adapted when the latter is flattened, to grip the sole and secure the washer against rotation relative thereto.

2. In a calk device for attachment to a shoe sole, a calk having a base; a screw member for connecting said calk to the sole; a washer insertable on said screw member, having projections formed thereon engageable with said sole; and ratchet means including opposed elements, intermediate said base and said washer for resisting rotation of said calk in unscrewing direction while permitting rotation in screwing direction.

3. In a calk device for attachment to a shoe sole, a calk having a base; means for securing said calk to the sole; a washer having means for gripping the sole, said washer being of such lateral extent relative to said base as to oppose marginal portions of the latter; ratchet teeth on said base; and means formed on said washer cooperable with said teeth to arrest rotation of said calk in one direction.

4. In a calk device for attachment to a shoe sole, a calk having a base; a screw member adapted to project outwardly beyond said sole, for connecting said calk to the sole; threaded means in said calk for threadedly receiving said screw member; a washer on and having a threaded connection with said screw member; and projecting means on said washer for gripping said sole and for holding said calk against adverse rotation.

5. In a device for securing a calk to a shoe sole, a washer; a tubular stem on said washer associated with said sole and adapted to receive a threaded member for securing a calk relative to the sole; a deformable portion on said washer, normally extending away from and adapted to be flattened relative to the sole; and projecting means on said deformable portion adapted when the latter is flattened, to grip the sole and secure the washer against rotation relative thereto.

6. In a device for securing a calk to a shoe sole, a washer; an internally threaded tubular stem on said washer, associated with said sole and adapted to receive a threaded member for connecting a calk to the sole; projecting means on said washer for holding the calk against inadvertent rotation; a deformable portion on said washer, normally extending away from and adapted to be flattened relative to the sole; and means on said deformable portion adapted when the latter is flattened, to grip the sole and secure and hold the washer against rotation relative thereto.

7. In a device for securing a calk to a shoe sole, an internally threaded tubular insert member in-

sertable in an aperture in the shoe sole; a deformable washer having a portion normally extending away from the sole and adapted to be flattened relative to the sole; a tubular stem on said washer, screwed into said insert member, having internal threads adapted to receive a threaded member for connecting a calk to the sole; and means on said deformable washer for gripping the sole when the washer is flattened.

8. In a device for securing a calk to a shoe sole, an internally threaded insert member, insertable in an aperture in the shoe sole; a washer; a tubular stem on said washer, screwed into said insert member, having internal threads adapted to receive a threaded member connecting a calk to the sole; and projecting means on said washer cooperable in holding the calk against inadvertent rotation.

9. In a device for securing a calk to a shoe sole, a deformable substantially U-shaped washer with the sides thereof normally extending away from and adapted to be flattened relative to the sole; an internally threaded tubular stem on said washer, associated with the sole and adapted to receive a threaded stud for connecting a calk to the sole; projecting means on said deformable washer for gripping the sole when the washer is flattened; and means on said washer for holding a calk against inadvertent rotation.

10. In a device for securing a calk to a shoe sole, a deformable substantially U-shaped washer with the sides thereof normally extending away from and adapted to be flattened relative to the sole; an inner face on said washer to engage said sole; a calk; an outer face on said washer to engage the calk; means to secure said washer to said sole; and means to secure said calk to said washer.

11. In a calk device for attachment to a shoe sole, an internally threaded tubular insert member, insertable in an aperture in a shoe sole; means on said insert member for arresting movement thereof downwardly through the sole; a washer; an internally and externally threaded tubular stem on said washer, screwed into said insert member; a calk having a threaded stud screwed into said tubular stem; and projecting means on said washer for holding said calk against inadvertent rotation.

12. In a calk device for attachment to a shoe sole; a washer; an internally threaded tubular stem on said washer, insertable in an aperture in the shoe sole; a screw member extending through said stem and having a free end portion adapted to project outwardly beyond said sole for receiving a threaded calk; means on said screw member for holding the same against rotation relative to said sole; and projecting means on said washer for gripping said sole.

13. In a device for securing a calk to a shoe sole, an internally threaded insert member, insertable in an aperture in the shoe sole; a washer; and a tubular stem on said washer, screwed into said insert member, having internal threads adapted to receive a threaded member connecting a calk to the sole.
